E. CUDNEY

DELAY ACTION EXPLORER

Filed Nov. 3, 1920

Patented May 15, 1923.

1,455,165

UNITED STATES PATENT OFFICE.

ELMER CUDNEY, OF STEGE, CALIFORNIA.

DELAY-ACTION EXPLODER.

Application filed November 3, 1920. Serial No. 421,488.

To all whom it may concern:

Be it known that ELMER CUDNEY, citizen of the United States, residing at Stege, in the county of Contra Costa and State of California, has invented new and useful Improvement in Delay-Action Exploders, of which the following is a specification.

This invention relates to a delay action exploder, of the type shown in my original application, Serial No. 349,866, filed January 7th, 1920, and of which the present application is a continuation in part.

It is common practice to set off explosive charges by delay action fuses, the interval of time being designated by the expression "delay action" accompanied by a numeral usually ranging from one to ten. It is thus possible to insure that a number of charges may be set off in succession and counted, so that a predetermined number of charges may be identified and the certainty of explosion ascertained. In carrying out this practice it is usual to assemble a spitter shell, a desired length of fuse and a fulminating cap, after which this exploder is imbedded within one of the sticks of dynamite to be exploded, thus insuring that the exploder will be maintained in a water proof condition, and that it may be easily ignited. There is often however, an ignition of the explosive charge within the spitter shell at the opposite end of the exploder and not within the fulminating cap. When this takes place two explosions are liable to occur simultaneously, thus making it impossible to tell whether or not all of the explosions have taken place, and thereby rendering further work dangerous. It is the principal object of the present invention to provide a delay action exploder which may be imbedded within a charge of dynamite or other explosive, there maintained in a water proof condition, and so constructed as to insure that electrical ignition of a charge within a spitter shell must cause ignition of the fuse only, and this in turn produce the ignition of the fulminating charge in the cap, thus eliminating premature explosions.

The present invention contemplates the use of a fuse having a central core of igniting material, and carrying a fulminating cap at one end and a spitter shell at its opposite end, said spitter shell being so designed as to securely hold an initial ignition charge in proper relation to an electrical

bridge theren, and in position over the end of the fuse, at the same time providing for a satisfactory escape of the products of combustion from the spitter shell without sufficient heat to directly ignite the main explosive charge.

The invention is illustrated by way of example by the accompanying drawings, in which:

Fig. 1 is a view in central longitudinal section, showing the exploder positioned within a stick of dynamite.

Fig. 2 is a view in section and elevation showing the bridge unit of the electrical conductors.

Fig. 3 is a view in elevation showing the electrical conductors and the manner in which the bridge is secured at the ends thereof.

Fig. 4 is a view in section and elevation showing a modified form of the invention used to ignite combustible liquids.

Referring more particularly to the drawings, 10 indicates a stick of dynamite which is covered with a wrapper 11. This wrapper, it will be understood, is treated to be impervious to moisture. A portion of the wrapper is cut away to form a hinged cover 12 along one side of the stick, after which a groove is dug in the dynamite to form the recess 13, within which the delay action exploder, or time fuse 14, is positioned. The portion 12 of the cover is then placed back and tied by strings 15, or other suitable fastening means. This is the method of application of the usual exploder to dynamite charges, although it will be understood that the present invention is applicable to other uses and conditions than those set forth in the drawings.

The exploder considered comprises a time fuse 16, on the lower end of which is crimped a fulminating cap 17, and at the opposite end of which a spitter shell 18 is crimped. The time fuse and fulminating cap are of common construction. The spitter shell, however, is of special design and constitutes an enlarged tubular body portion 19 drawn at one end to form a restricted neck 20 into which the time fuse is crimped. A large exploder capsule 21 is seated within the body portion adjacent the neck 20. This capsule is preferably transparent being made of gelatin or celluloid and is formed in two parts so that it may be easily re-

moved. The lower end of the capsule has an ignition opening 22 directly in registry with the core of the fuse 16, the upper end of the capsule is formed with small perforations through which electrical conductors 23 and 24 may pass. Vent perforations 25 are also formed in the top of the large capsule 21 to permit the escape of gas of combustion.

10 The electrical conductors 23 and 24 are insulated throughout most of their length, and have bared ends which extend through the perforations in the end of the large capsule and terminate at a point near the ignition opening 22. The terminating ends of the conductors are formed with the V shaped groove 26, more clearly shown in Fig. 3. These grooves are provided as a seat for a bridge 27, which is properly secured to the ends of the two conductors and spans the gap there between and soldered, as shown more clearly in Fig. 2. This bridge is preferably of platinum, and of a sectional area and resistance to be readily 20 heated, and thereby ignite a quantity of explosive paste, meal powder and gun cotton disposed around these terminals and indicated at 28.

The terminals and the explosive there 30 around are enclosed by a small capsule 29. This capsule has a firing opening 30 in its lower end disposed in registry with the firing opening 22 of the large capsule. In the top portion of the small capsule is formed 35 of the plurality of vent openings 31, and other openings through which the bared terminals of conductors 23 and 24 may extend. In this manner the charge 28 may be permanently held in intimate contact with 40 the bridge 25 and over the core of the fuse 16, thus insuring a certainty of fire, and at the same time protecting the bridge from breaking and the charge from displacement.

When ignition of the explosive charge 28 45 takes place considerable gas will be generated by the combustion. This gas must be allowed to escape at a sufficiently low temperature to eliminate possibility of directly igniting the surrounding dynamite. 50 A filter plug 32 is therefore provided to partially stop the opened end of the spitter shell and to allow a slow filtration of the gases therethrough, in a manner to insure that they shall be properly cooled.

55 This plug is cylindrical in shape, being intended to fit snugly within the spitter shell, and is provided with an annular groove 33 around its central portion to allow circulation of gas. The plug is further 60 formed with a central cavity 34 in communication with the groove 33 through ducts 35. It is also to be understood that the same purpose might be accomplished by spinning a protruding bead in the spitter shell 65 around the plug to obtain an annular groove

33, having the same functions as shown in the drawings. Vent openings 33' are formed through the sides of the spitter shell and communicate with the groove 33, so that the gas can pass therethrough. Attention 70 is directed to the fact that the vents in the plug are positioned above the vents in the spitter shell, so that the gas and fire will have difficulty in passing out through the 75 vent openings in the spitter shell and in reaching the surrounding explosive.

In the drawings the filter plug is shown in several forms. In Fig. 1 it is shown as comprising a core portion 36, preferably formed of plaster of paris, or other similar material, and over which a metal shell 37 is disposed. In Fig. 2, the metal shell 37 is shown as filled with asbestos fabric 38, which surrounds the conductors 23 and 24, while permitting them to pass through the 80 outlet openings in the end of the plug. 85

The mouth of the spitter shell is preferably formed with a series of beads by which annular grooves are made within the shell. These grooves serve as bonds for a sealing material 39, which material is preferably 90 virgin rock sulphur melted and poured into place. This material is used due to its well known water proofing qualities, which 95 would prevent moisture from seeping into the shell.

The assembled exploder is covered with a jacket 40, preferably made of rubber, or other protective material, thereafter being 100 covered with a coat of some water proofing solution. In this manner the exploder may be preserved for considerable time while entirely submerged in water.

Referring more particularly to Fig. 4, it 105 will be seen that the electrical conductors 23 and 24 are fitted with the same large and small capsules 21 and 29, as used in the other form of the device. These capsules are enclosed within a paper shell 41, which 110 contains an igniting charge 41'. A plug 42 closes the open end of the shell, while a filter member 43 surrounds the conductors, and restricts the gas sufficiently to permit it to cool as it escapes through vent openings 44, and break the covering 45. The member 43 is here shown as of asbestos fabric, while the covering 45 is preferably paper.

With this form of invention it is possible 115 to ignite hydro carbon fuel in smudge pots and to ignite any other liquid at a remote point from the control switch or blasting machine.

It is desirable to hold the two electrical conductors in fixed relation to each other. This is done in some instances by twisting 120 the wires, as shown in Fig. 2, and at other times by securing the wires in fixed relation to each other by a clip 46 as shown in Fig. 3.

125 In operation of the present invention the exploders are assembled with the fuse 16 cut 130

any desired length to agree with the standard delay action desired. The fulminating cap is then crimped on the bottom end and the spitter shell crimped at the opposite end. This shell will, of course, have been previously assembled. This is done by preparing the electrical conductors, then passing them through the tops of the large and small capsules. The explosive charge 28 is then passed within the top of the small capsule after which the bottom of this capsule is put on and then the bottom of the large capsule. These assembled members are then inserted into the spitter shell and brought to seat against the restricted neck portion thereof. The filter plug is either before or afterwards strung onto the conductors, and then fitted within the shell with its annular groove 33 in registry with the vent openings 33'. The sealing material 39 is then filled into the end of the shell, and after the shell has been applied to the fuse the assembled unit is covered with the casing 40. This is thereafter treated with a protective coating of a water proofing material. The exploder may then be used as desired. Although, as before stated, it is common practice to imbed it within the stick of dynamite and thereafter tie it in place and in condition to be practically impervious to moisture. The conductors 23 and 24 may be led to a control board blasting machine at any distance, and an electric current established through them at will.

35 When an electric current is established through the conductors the bridge 27 will be heated and the explosive charge 28 ignited. This charge will directly fire through the openings 22 and 30 and ignite the end 40 of the fuse core after which combustion will take place throughout the length of the fuse and finally set off the fulminating cap. When the charge 28 is first ignited the gas generated will pass out through the small capsule 29, through the vents 31, and will then pass from the large capsule through the vents 35. The gas will then pass into the cavity 34 of the filter plug and finally pass out through the vent openings 33'. The pressure of this gas is usually sufficient to burst the cover 40, which is disposed over the openings 33'.

It will thus be seen that by the invention here disclosed it is possible to ignite an explosive charge with any desired delay action, and to furthermore insure that the charge will be ignited even though the exploder is positioned within water or in other damp and unfavorable locations.

60 While I have shown the preferred form of my invention, it will be understood that various changes may be made in the combination, construction and arrangement of parts, without departing from the spirit of the invention as claimed.

Having thus described my invention, what I claim and desire to secure by Letters Patent is:

1. A delay action exploder including a fulminating cap, a fuse secured to one end thereof, a container for an ignition charge of explosive, a second container inclosing the first named container to form a combustion chamber, a spitter shell having one end closed inclosing said containers and secured to the fuse, electrical exploding means extending into the spitter shell and into the first named container, and a filter plug between the said containers and the closed end of the spitter shell, and means to circulate the gases of combustion from the inner container through the filter plug. 75

2. A spitter shell consisting of an outer tubular casing having one end closed, electrical exploding means extending into the end of said shell, an initial explosive container secured around the end of the electrical igniter, a second container enclosing the first-named container to form a combustion compartment, a filter plug between said second container and the closed end of the spitter shell, and means to circulate the gases of combustion from the inner container through the filter plug. 85

3. The combination with a time fuse of a spitter shell secured at one end to the time fuse, a pair of electrical conductors extending through the end of the shell and having an electrical resistance bridge at their terminals, a capsule within which said terminals are enclosed and enclosing a charge of explosive material in contact with the bridge, said capsule having vent openings in its end, a second capsule enclosing the first-named capsule and forming a surrounding combustion compartment, and also having vent openings, a moisture-resisting means closing the end of the spitter shell through which the conductors pass, said spitter shell having vent openings in its side walls between the exterior capsule and the end closure, and filtering means between said members. 100 105 110

4. An electrical exploder including a pair of electrical conductors, an explosive charge containing capsule within which the terminals of said conductors are located, said terminals having grooves in their ends, a resistance bridge connecting said grooves and located in contact with the explosive charge, and a second capsule enclosing the first-named capsule to form a combustion chamber, said capsules having registered firing openings in their ends. 115 120

5. The combination with a fuse a tubular metallic shell member secured at one end thereto, an inflammable substance contained within said shell for igniting said fuse, a plug member for closing one end of the shell and for forming a compartment within the 125 130

shell to receive the inflammable substance, filtering material within said chamber and intermediate the inflammable substance and the plug and a normally closed vent formed 5 through the wall of said chamber for permitting the escape of gas generated within the shell after it has passed through the filtering material.

6. In combination with a fuse a tubular 10 metallic shell positioned over and secured to one end thereof, filtering material disposed within the shell and spaced from the end of the fuse to form a chamber, a plug closing the opposite end of the shell, inflammable 15 material disposed adjacent the end of the fuse and within said chamber, electric means for producing the ignition thereof, and normally closed vents in the wall of said shell to permit the escape of gases generated by 20 the inflammable material after it has passed through the filtering medium.

7. In combination with a fuse a tubular metallic shell positioned over and secured to one end thereof, an ignition chamber formed within the shell adjacent the fuse, 25 a plug closing the opposite end of the shell, inflammable material within the ignition chamber, electric ignition means therefor, normally closed vent openings in the side of the shell, and baffle means intermediate 30 said openings and the ignition chamber whereby the temperature of the gases generated within said chamber will be lowered before passing outwardly through the vent openings. 35

In testimony whereof I have hereunto set my hand in the presence of two subscribing witnesses.

ELMER CUDNEY.
